UNITED STATES PATENT OFFICE.

CARL BERGFELD, OF BERLIN-WILMERSDORF, GERMANY.

APPARATUS FOR TRANSMITTING THE POSITION OF SIGNALS.

Application filed November 6, 1924, Serial No. 748,264, and in Germany October 20, 1924.

My invention relates to such apparatus as has been already used to transmit the position of the signals to the train itself, for instance to the driver's cabin on a locomotive. Its object is

5 1. To increase the safety of the traffic and especially to avoid the shocks which occurred hitherto when a striker hit against the lever of such apparatus,

10 2. To assure that the position of the signals will be transmitted to the cabin of the driver,

15 3. To assure that the train will be stopped automatically, when it passes the main-signal, and

4. To assure that the apparatus cannot be tampered with.

I attain these objects in the following manner:

20 Near the main-signal and the advance-signal are arranged a pair of butting faces or the like, which act with as small a shock as possible and of which the first is connected with the advance-signal, the second with the main-signal.

25 The first butting-face transmits the position of the advance-signal to the driver's box by showing a visual signal-disc, when the line is blocked, i. e. when the signal is in the "danger"-position.

30 The signals with their butting-faces are usually arranged at such a distance from each other that the train can be stopped between them. The second butting-face withdraws the signal-disc into its invisible position, if the track has been cleared,

35 while the train runs from the first butting-face to the other. On such lines with little traffic where there are no advance-signals the butting face which is otherwise connected with the advance signal is placed at such a distance before the main-signal, that the train can be stopped before it reaches the latter.

40 The first butting face, belonging to the advance signal, in the direction in which the train is running, is arranged in such a manner that it is out of the way of the roller placed below the engine when the line is free. The second butting face near the main-

45 signal is then so placed that the roller cannot act on it. In this case the signal-disc in the driver's cabin remains invisible.

50 If the line is blocked however the first butting face is so positioned as to hit the roller beneath the engine. By suitable means the revolution of the roller or its

lateral movement is transmitted to the signal-disc which is caused to appear, which appearance can be accompanied by an acoustic signal. The second butting face belonging to the main-signal is then in such position that the roller cannot strike it. The signal-disc in the driver's cabin remains therefore visible, even when the train runs past the main-signal. If the driver has stopped his train before the main-signal and this signal is then set at "line clear" the position of the butting faces is reversed. The first butting face moves out of the way of the roller and the second into its path. 60 If the driver now sets his train again in motion and it passes the main-signal-butting face the signal disc on the engine is withdrawn and becomes again invisible. Should the driver however run past the 65 main-signal while it is blocked the signal in his cabin will remain visible and can only be rendered invisible by hand. In order to control the driver and to be able to call him to account for running past a danger signal 70 the apparatus is so constructed that the removal of the disc from its visible position is only possible after detaching a lead seal.

75 With the transmittal of the signal an arrangement may be provided by means of 75 which the train can be automatically stopped if it should run past the main-signal.

80 The butting faces may consist of flexible steel-bands; the roller may be arranged 85 vertically or horizontally.

85 My invention is illustrated in the accompanying drawing in which

90 Fig. 1 is a diagrammatic plan-view of the apparatus between the rails, showing the advance and main signals in the "clear" position.

95 Fig. 2 is a diagrammatic perspective view of the apparatus similar to Fig. 1 but showing both the advance and main signals in 100 the "blocked" position.

100 Fig. 3 is a diagrammatic elevation showing the apparatus on the engine for operating the audible signal and signal-disk in the engine cabin and the automatic braking 105 device from the roller.

105 Fig. 4 is a diagrammatic view of part of the braking device.

110 As shown in Figs. 1 and 2, between rails c and d are arranged the ramp rails c and d spaced apart and arranged adjacent opposite rails, the ramp rail c being disposed adjacent the

advance signal *a*, and the ramp rail *d* being disposed adjacent the main signal *b*. Ramp rails *c* and *d* are connected by suitable link mechanism to operate simultaneously where-
5 by one ramp rail will be parallel with track *z* while the other ramp rail will be inclined towards the center of the track in position to contact with a roller *e* depending from the underside of the engine.

10 As shown, a link *c'* for operating ramp rail *c* is connected to one arm of a bell crank lever *4* disposed beside the track, the other arm of lever *4* being connected to a rod *2* disposed substantially parallel with the track and operated by a hand lever *7*. A bell-crank lever *3* opposite advance signal *a* has one arm connected to rod *2* and its other arm connected to a link *a'* operating the advance signal *a*. A link *d'* similarly operating ramp rail *d* is connected to rod *2* through a bell crank lever *6*; and a bell crank lever *5* opposite main signal *b* has one arm connected to rod *2* and the other arm connected to a link *b'* operating the main signal. Links *c'* and *d'* are of such length that when hand lever *7* is thrown in "clear" position (Fig. 1) ramp rail *c* will lie parallel to track *z* out of the path of roller *e*, while ramp rail *d* will be inclined 20 inwardly so that same projects into the path of roller *e*. When however hand lever *7* is thrown into "blocked" position (Fig. 2) the positions are reversed, ramp rail *c* being inclined into the path of roller *e* while ramp rail *d* lies parallel with the track.

Any other types of ramp rails and link mechanisms however may be used. Also the apparatus may be used for railroads having double tracks, or for single track railroads where the trains run only in one direction.

As shown in Fig. 3, roller *e* is mounted on a shaft *f* journaled in casing *x* below the engine, which casing is pivotally mounted upon an axially movable rod *l* so as to yield laterally when roller *e* strikes ramp rails *c* and *d*, casing *x* being normally retained in central position with respect to the track by means of spring *h* attached to casing *x* and to a fixed support. One end of shaft *f* extends below the casing *x* and its lower end is covered by a housing *y* which can only be opened after breaking a lead seal *y'* to adjust the shaft *f* for the purpose hereinafter set forth. Rod *l* extends upwardly into the cab of the engine and carries on its upper end a signal *m* which is normally covered by a suitable shield when the rod *l* is in lowered position, but which is projected upwardly into displayed position when the rod *l* is raised. On shaft *f* is a worm *i* meshing with a segmental gear *k* pivoted at *k'* in casing *x*, and having a radial arm *k'* connected to rod *l*. Hence when shaft *f* is rotated in one direction worm *i*

will actuate gear *k* and arm *k'* will raise rod *l* displaying disk *m* as shown in dotted lines in Fig. 3. When however shaft *f* is rotated in the opposite direction rod *l* and disk *m* will be lowered in a similar manner. 70

Rod *l* also actuates an audible signal in the engine cab, which signal consists of a bell *o* having a clapper *p* operated by a series of teeth or projections *n* on rod *l* when the same is moved therewith. 75

The means for automatically stopping the train in event the engine should run past the main signal, consists of a bell-crank lever *q* having one arm attached to rod *l* and the other arm connected to a link *r*, the other end of which is connected to arm *s'* of a bell-crank lever *s*. Above the pivot *s''* of bell-crank lever *s* is a valve *t* connected in the air brake or other piping which may control the throttle lever of the locomotive, 80 automatically. Valve *t* is normally held shut by a lever *u* pivoted adjacent valve *t*, and a breakable member *v*, of wire or the or the like, connects the free end of lever *u* with the arm *s'* of lever *s*. When rod *l* 90 is in lowered or "clear" position the arm *s'* of bell-crank lever *s* is swung into retracted position shown in dotted lines in Fig. 4, but when rod *l* is in raised or "blocked" 95 position arm *s'* of lever *s* is projected into the position shown in full lines in Fig. 4 so that member *v* will lie in the path of a striker *w* (Figs. 1 and 4) mounted beside the track *z* and member *v* will be broken to automatically release valve *t* when the engine runs therewith, and the engine will 100 hence be automatically stopped.

When the track is "blocked" (Fig. 2), if the engine should run past advance signal *a*, roller *e* will be revolved by ramp rail *c* in 105 the direction of the arrow, and the rotation of shaft *f* will raise rod *l* and display the signal disk *m* in the engine cabin and will also sound the audible signal *o*, calling the driver's attention to the fact that the track is "blocked" so that he may stop the train before main signal *b* is reached. 110

If however the track has been cleared while the engine is passing from the advance signal to the main signal as shown by Fig. 1, the ramp rail *d* will be inclined into the path of roller *e* and hence when the train runs past the main signal *b* roller *e* striking ramp rail *d* will revolve shaft *f* in the opposite direction, in consequence of which the rod *l* and signal disk *m* will again be lowered and the train may continue its route. 115

If, however, the train runs past the main signal *b* when set in "blocked" position, arm *s'* of bell-crank lever *s* remains projected in position indicated in full lines in Fig. 4 holding member *v* in the path of striker *w* which is arranged beside the track near the main signal *b* (Figs. 1 and 4) and member 125

v will be thereby broken. Valve lever *u* being thus released opens the automatic brake valve *t* bringing into action the emergency brake of the engine. Also if the engine runs past the "blocked" main signal *b* the signal disk *m* in the engine cabin will remain in raised or displayed position and can only be returned by hand to its normal lowered position after breaking the seal of housing *y* and re-setting shaft *f* proving that the engineer disregarded the signals.

10 I do not limit my invention to the exact form shown in the drawings for obviously changes may be made within the scope of the 15 claims.

I claim:

1. Apparatus for transmitting the position of signals to the cabin of a train, comprising a shaft on the train intermediate the 20 rails; an advance signal; a main signal; a pair of opposed ramps on the track intermediate the rails, one in advance of the other, the advance ramp being actuated by the advance signal, and the other by the 25 main signal; a roller on said shaft adapted to contact with said ramps; said ramps being adapted to rotate the roller in opposite directions; and means cooperating with said shaft for actuating a signal in the cabin.

30 2. In apparatus as set forth in claim 1,

said shaft being mounted in a swingable frame; and yieldable means for normally swinging the frame to center the roller between the rails.

3. In apparatus as set forth in claim 1, 35 the advance ramp being placed at such a distance from the second ramp that the train can be stopped between the two ramps.

4. In apparatus as set forth in claim 1, 40 said means comprising a worm on said roller shaft; a pivoted lever; a segmental gear on said lever actuated by said worm, a longitudinally movable rod extending into the cabin and carrying said signal, and said lever being connected with said rod, whereby as the 45 worm is rotated in either direction the signal rod will be actuated accordingly.

5. In combination with apparatus as set forth in claim 1, a longitudinally movable rod extending into the cabin and carrying 50 the signal; means for operating the rod from the roller shaft; a valve; a bell crank operated by the rod; a frangible link connecting the bell crank with the valve; and a striker adjacent the link whereby when the link 55 strikes the striker the link will be broken and the valve actuated.

6. In apparatus as set forth in claim 1, the ramps comprising pivoted bands.

CARL BERGFELD.
